UNITED STATES PATENT OFFICE.

ELMER S. SMITH, OF BOUND BROOK, NEW JERSEY, ASSIGNOR, BY MESNE ASSIGNMENTS, TO DEVAC AUTO COMPANY, OF EAST ORANGE, NEW JERSEY, A CORPORATION OF NEW JERSEY.

INTERNAL-COMBUSTION ENGINE.

No. 861,614.

Specification of Letters Patent.

Patented July 30, 1907.

Application filed July 16, 1906. Serial No. 326,311.

To all whom it may concern:

Be it known that I, ELMER S. SMITH, a citizen of the United States, and a resident of Boundbrook, in the county of Somerset and State of New Jersey, have invented certain new and useful Improvements in Internal-Combustion Engines, of which the following is a specification.

The invention relates to improvements in internal combustion engines, and it consists in the novel features, arrangements and combinations of parts herein-after described, and particularly pointed out in the claims.

The object of the invention is to produce an internal combustion engine of maximum economy and high efficiency, and in the use of which undue heating of the cylinders is avoided and the expansive force of the motive fluid utilized to the maximum degree.

In carrying out my invention, in a preferred form, I provide an engine composed of four parallel cylinders containing pistons connected with the crank-shaft and connect the first and fourth cylinders at their upper ends by a passage and the second and third cylinders at their upper ends by a similar but independent passage, the cranks of the shaft being so disposed that when the pistons in the first and fourth cylinders are in their upper position the pistons in the second and third cylinders will be in their lower position, and that when the pistons in the first and fourth cylinders are in their lower position the pistons in the second and third cylinders will be in their upper position. The engine thus constructed and arranged is provided with a proper exhaust from each of the cylinders, as usual, and also with means for admitting air to the ports leading to, say, the third and fourth cylinders and gasoline or other motive fluid to the ports leading to, say, the first and second cylinders, or for cutting off the air entirely and admitting the motive fluid to the inlet ports of all the cylinders. In the construction described the pistons in the first and fourth cylinders always move in unison and in the same direction and the pistons in the second and third cylinders always move in unison and in the same direction. The pistons within the cylinders cover and uncover the ports leading thereto and therefrom.

In the use of the engine I admit the gasoline or other motive fluid to the inlet ports of all the cylinders, when occasion requires or the same seems desirable, as when an automobile equipped with the engine is being driven up a steep incline, and at other times I admit air to one and gasoline or other motive fluid to the other of a connected pair of cylinders the air and motive fluid on the ascent of the pistons in said cylinders being compressed in the upper ends thereof and the

gasoline being ignited in the upper end of the cylinder to which it was admitted, with the result that the heat due to such ignition will extend through the passage leading to the other cylinder and effect the expansion of the air therein, whereby power is generated in the upper ends of both cylinders and the pistons therein are driven downwardly and impart their power to the crank-shaft. I thus charge one cylinder with the gasoline or other motive fluid and the other with air and ignite the said charge of motive fluid, allowing it to act against the piston in its cylinder and flow into and commingle with and expand the air in the other cylinder. In thus employing air in one and gasoline or the like in the other cylinder, I am enabled to utilize the heat of the ignited charge to the maximum degree as power and avoid unduly heating the cylinders, the air absorbing and utilizing that part of the heat which is ordinarily wasted and discharged through the exhaust in other types of internal combustion engines known to me.

The invention will be fully understood from the detailed description hereinafter presented, reference being had to the accompanying drawings, in which:

Figure 1 is a front elevation of an internal-combustion four-cylinder engine constructed in accordance with and embodying my invention; Fig. 2 is a vertical transverse section of same on the dotted line 2-2 of Fig. 1; Fig. 3 is a vertical longitudinal section of same on the dotted line 3-3 of Fig. 2; Fig. 4 is a detached top view of the pipe and valve casing through which the motive fluid and air are respectively supplied to the cylinders; Fig. 5 is a horizontal longitudinal section of same on the dotted line 5-5 of Fig. 1; Fig. 6 is a vertical longitudinal section of same on the dotted line 6-6 of Fig. 5 and illustrating the valve positioned to admit the motive fluid to the left hand cylinders and air to the right hand cylinders, and Fig. 7 is a like view of a detached portion of same, the valve being positioned to cut off the air supply and admit the motive fluid to both the left hand and right hand cylinders.

In the drawings, 10, 11, 12 and 13 designate the respective cylinders, and 14, 15, 16 and 17 the respective pistons or plungers within said cylinders and which are by means of pivoted piston rods 18 connected with the crank shaft 19 mounted within the lower section 20 of the engine frame and which section forms within it a series of air chambers 21 respectively connected with the respective cylinders by means of ports 22 (Fig. 2). The cranks for the piston rods of the pistons 15, 16 are parallel with and extend in the same direction as each other, and the cranks for the piston rods 18 of the pistons 14, 17 are parallel with and ex-

tend in the same direction as each other, as shown in Fig. 3, and these several cranks perform their rotation within the respective chambers 21.

The cylinders 10, 11, 12, 13 are equipped with usual 5 sparking or ignition devices 23 (Fig. 2) and the cylinders 10, 13 are at their upper ends connected by a passage 24 (Fig. 3), while the upper ends of the cylinders 11, 12 are connected at their upper ends by a passage 25, the passages 24, 25 being formed within a casing or 10 cap applied upon the upper ends of the cylinders and there secured by means of suitable bolts 26 (Fig. 2).

The cylinders 10, 11, 12, 13 are at a suitable point 15 provided with exhaust ports 27 (Fig. 2) leading to a general exhaust pipe 28 secured to and extending along said cylinders, and below the exhaust pipe 28 the cylinders are formed with inlet ports 29 which communicate with a pipe 30 for the supply of the air and motive fluid or for the introduction of the motive fluid alone.

20 The pipe 30 at its central portion is formed with a valve casing 31 within which is mounted a rotary valve 32 and into which valve, which is hollow, is led a pipe 33 for the supply of the air.

The valve 32 is formed in its periphery with a port 25 34 which may be turned into line with the pipe 39 at one side or the other of the center thereof, as shown in Fig. 6, or to a position in which said port 34 shall be closed from communication with either end of said pipe, as shown in Fig. 7.

30 The valve 32 is provided with a stem 35 upon which is secured a crank arm 36 to be operated by any suitable means for setting the valve 32 either in the position in which it is shown in Fig. 6 admitting air to the right hand end of the pipe 30, or in the position shown in Fig. 35 7 for cutting off the air from both ends of the pipe 30. It is to be observed that the valve 32 when in the position shown in Fig. 6 will admit air into the right end of the pipe 30 and cut off any communication of the air from the pipe 33 with the left hand end of said 40 pipe 30.

The combustible motive fluid is admitted to the valve casing 31 from the pipe 37, and the position of the valve 32 determines whether the motive fluid shall only pass into the left hand end of the pipe 30 or into 45 both ends of said pipe. When the valve 32 is in the position shown in Fig. 6 the air is admitted to the right hand end of the pipe 30 and the motive fluid is at the same time admitted into the left hand end of said pipe, while when the valve 32 is turned to the position shown 50 in Fig. 7, the motive fluid may pass freely to both ends of the pipe 30 and the air is entirely cut off from said pipe. The right hand end of the pipe 30 communicates with the inlet ports 29 of the cylinders 12, 13, (Fig. 1) and the left hand end of said pipe communicates through the ports 29 with the cylinders 10, 11, 55 (Fig. 1) and in the position of the valve 32 shown in Fig. 6 air is admitted to the ports 29 of the right hand cylinders 12, 13, while the motive fluid is admitted to the ports 29 leading to the cylinders 10, 11.

60 The ports 22 leading into the cylinders from the crank-pit chambers 21 enter said cylinders at a point at which they will be uncovered when the pistons are in their lower position, and the exhaust ports 27 are likewise so disposed that they are uncovered when the 65 pistons reach their lower position, as shown in Fig. 2.

The ports 27 are greater in width than the ports 22 so that they become partly uncovered before the ports 22 are uncovered. The inlet ports 29 are covered by the pistons when the latter are in their lower position, and they become uncovered when the pistons are in their 70 upper position. When the pistons are in their upper position they close both the ports 22 and 27 and open the ports 29.

In the employment of my invention it is my purpose in one use thereof, to admit air only to the cylinder 13 75 and gasoline or other motive fluid only to the cylinder 10, and air alone to the cylinder 12 and the motive fluid alone to the cylinder 11, the cylinders 11, 12 being coupled together by the passage 25 and the cylinders 10, 13 being coupled together by the passage 24. 80

The motive fluid and air admitted to the cylinders 10, 11 and 12, 13 respectively pass through the inlet ports 29 when the pistons move upwardly and uncover said ports and cover the ports 22, 27, and first enter the chambers 21 and then upon the descent of the pistons are caused to pass upwardly through the ports 22 into the cylinders, the motive fluid and air respectively entering their cylinders with some considerable force upon the uncovering of the ports 22 by the descending pistons and being deflected upwardly 90 in said cylinders by deflectors 40 provided upon the upper ends of the pistons. Just prior to the pistons, on their descent, uncovering the ports 22 to admit the motive fluid and air, they partly uncover the exhaust ports 27 for the discharge of the waste products from the 95 cylinders. The upward sweep of the motive fluid and air aids in clearing out the waste products from the cylinders.

The operation of the engine will be largely understood from the detailed description hereinbefore presented. 100 When the valve 32 is in the position in which it is shown in Fig. 6 the air is admitted to the inlets 29 for the cylinders 12, 13 and the motive fluid is admitted to the inlets 29 for the cylinders 10, 11, said motive fluid and air only entering into the chambers 21 for said cylinders when the pistons move upwardly. In the position of the parts shown in Fig. 3 combustion is taking place in the cylinders 10, 13 and motive fluid and air are respectively being admitted to the respective chambers 21 for said cylinders, the inlets 29 for the cylinders 11, 12 being closed by the pistons 15, 16. Upon ignition taking place in the upper end of the cylinder 10 the heat expands through the passage 24 and there is set up a mutual coaction of the gases from the cylinder 10 with the air from the cylinder 13, the air expanding and with the gases driving the pistons 14, 17 downwardly for operating the shaft 19. The downward movement of the pistons 14, 17 takes place with the upward movement of the pistons 15, 16 and upon their arriving at their upper position combustion will take place and the heat and gases of the cylinder 11 will combine with the air in the cylinder 12 and effect the downward movement of said pistons 15, 16. One of the desirable objects accomplished by my invention is the provision of the connected cylinders with means for admitting air to one cylinder and the motive fluid to the other cylinder, so that upon combustion taking place in the compression end of the cylinder to which the motive fluid is admitted, the air may be affected by the heat thus produced and contribute to such combustion, whereby economy

efficiency and increase of power are attained without unduly heating the cylinders and without undue waste of the heat units either through the exhaust ports or through the employment of the usual cooling jackets 5 applied to the cylinders of internal combustion engines. A large percentage of the heat generated in internal combustion engines is absorbed through the cooling jackets and a larger percentage of said heat issues through the exhaust, and it is my purpose to utilize a 10 part of this heat in gaining power, which I do by the employment of the cylinders in pairs and the connection of the compression ends of the cylinders by communicating passages. I prefer to arrange the passages 24, 25 connecting the compression ends of the cylinders 15 in the manner shown in Fig. 3, the two outside cylinders being connected together and the two inside cylinders being connected together, so as to produce a nicely balanced engine, but I do not limit myself to the employment of four cylinders, nor to the special arrangement 20 of the passages 24, 25 shown. As many cylinders as desired may be employed and they will be coupled together in pairs by communicating passages at their compression ends. The engine of my invention will thus comprise either one pair of cylinders or as 25 many pairs of cylinders as may be required or deemed expedient.

What I claim as my invention and desire to secure by Letters-Patent, is:

1. In an internal combustion engine, a series of cylinders connected in pairs by passages at their compression ends, and means for admitting air to one cylinder of a connected pair and the motive fluid to the other thereof, and for cutting off the air and admitting the motive fluid to both cylinders, as occasion may require; substantially 30 as set forth.

2. In an internal combustion engine, a series of cylinders

connected in pairs by passages at their compression ends, inlet ports to all of said cylinders, a pipe communicating with all said ports, a valve casing in said pipe intermediate the cylinders of said pairs, a hollow valve in said casing having a port adapted to be placed in communication with said pipe at one side of said casing or to be closed by said casing, means for setting said valve, and air and motive fluid connections leading respectively into said valve and said valve casing; substantially as and for the 40 purposes set forth.

3. In an internal combustion engine, a series of cylinders connected in pairs by passages at their compression ends, pistons in said cylinders, a crank-shaft, and rods connecting said pistons with the cranks of said shaft, said cranks being so disposed that the pistons of the respective pairs of cylinders move in unison and in the same direction, combined with means for admitting air to one cylinder of a connected pair and the motive fluid to the other thereof and for cutting off the air and admitting the motive fluid to both cylinders, as occasion may require; substantially 50 as set forth.

4. In an internal combustion engine, a pair of cylinders connected by a passage at their compression ends, and means for admitting air to one of said cylinders and the motive fluid to the other thereof and for cutting off the air and admitting the motive fluid to both cylinders, as occasion may require; substantially 55 as set forth.

5. In an internal combustion engine, a pair of cylinders connected by a passage at their compression ends, inlet ports to said cylinders, a pipe communicating with all said ports, a valve casing in said pipe intermediate said cylinders, a hollow valve in said casing having a port adapted to be placed in communication with said pipe at one side of said casing or to be closed by said casing, means 60 for setting said valve, and air and motive fluid connections leading respectively into said valve and said valve casing; substantially as and for the purposes set forth.

Signed at New York city, in the county of New York and State of New York this 14th day of July A. D. 1908. 65

ELMER S. SMITH.
